UNITED STATES PATENT OFFICE.

HENRY CASEBOLT, OF SAN FRANCISCO, CALIFORNIA.

CONSTRUCTION OF CABLE-RAILROADS.

SPECIFICATION forming part of Letters Patent No. 237,814, dated February 15, 1881.

Application filed December 11, 1880. (No model.)

To all whom it may concern:

Be it known that I, HENRY CASEBOLT, of the city and county of San Francisco, and State of California, have invented certain Improvements in the Construction of Endless Cable-Ways; and I hereby declare the following to be a full, clear, and exact description thereof, reference being had to the accompanying drawings, making part of this specification, in ⁵ which—

Figure 1 is a perspective view of one of the cast-iron brackets used in my improved construction. Fig. 2 is a plan view of the same. Fig. 3 is a face view of the same, showing the ¹⁵ end of the tie and slot-rail in position. Fig. 4 is a vertical longitudinal section through the line $x x$ of Fig. 2. Fig. 5 is a perspective view of the frame-work for the tunnel and track. Fig. 6 is a vertical cross-section of the ²⁰ same.

In all cable-ways for the transportation of street-railway cars by means of an endless traveling cable laid under ground it is highly desirable to have the edges of the slot through, ²⁵ which the gripe-shank passes adjustable to and from each other, in order to compensate for unequal wear, warping of the slot-rails, or, when occasion requires, to raise the cable through the slot and above the surface. It is ³⁰ also desirable to construct the slot-rails in the most economical manner and still retain great strength, and the purpose of my invention is to attain these objects.

My invention consists, first, in an adjustable ³⁵ cast-iron bracket secured to the ties and supporting the slot-rails; secondly, in a flat slot-rail rolled with a heavy bead or rib on one edge; and, thirdly, in certain details of construction, as hereinafter more fully described ⁴⁰ and claimed.

In order that those skilled in the art may make and use my invention, I will proceed to describe the manner in which I have carried it out.

In the said drawings, J J are the foundation-timbers, which are laid at the bottom of the trench into which is to be built the tube or tunnel, these timbers J being provided with ⁴⁵ ribs K, to sustain the thrust of the sheathing, ⁵⁰ as hereinafter set forth. Upon J rest posts L, which, in turn, support the ties B B, on

which rest the stringers N N to receive the rail O. The distance between the posts L L and the ends of the ties determines the width of the tunnel opposite their respective positions. ⁵⁵

Upon the end of each tie is a cast-iron bracket, A, projecting over the end of the tie toward the central line of the tunnel. The faces of these brackets sustain the slot-rails H ⁶⁰ H, which are left sufficiently far apart to form a slot, R, for the passage of the shank of the griper. The brackets A are cast with slots D, through which pass bolts C, to secure them to the ties, and with holes, through which pass ⁶⁵ bolts I, to fasten to them the slot-rails, and on their faces they have projecting ledges i i, upon which rest the lower edges of the slot-rails, and on the sides adjacent to the lowest points of their faces are right-angle-triangular ⁷⁰ lugs a, to receive and sustain the ends of angle-iron stringers P, the upper edge of the angle-iron stringer resting against the lower edge of the slot-rails H, to prevent the entrance of dirt into the tunnel. ⁷⁵

The vertically-arranged planks S, which form the body of the tunnel, have their lower ends resting against ribs K on the foundation-timbers, and their upper ends rest against the angle-iron stringers P P. The side surfaces of ⁸⁰ the brackets, ties, and posts are all in line, and consequently the edges of the planks S set close against all of them, and leave no openings for the earth to enter the tunnel when the framework is covered. ⁸⁵

Experiment teaches me that the form of slot-rail shown, having the heavy rib O' and the downwardly-projecting web or flange p, embodies great wearing capacity, ease of fastening, and economy of production. I describe ⁹⁰ this slot-rail with the heavy rib O', in contradistinction to the slot-rails heretofore used, made of angle-iron rolled for the purpose, which are liable to be mashed down along the edges of the slot, whereas my slot-rail is in ⁹⁵ form the same with the ordinary commercial flat rail used for street-railroads, and the heavy rib offers a resistance to the wheels of heavy vehicles that prevents any distortion at the edges of the slot. The slots D in the brackets ¹⁰⁰ A allow an amount of longitudinal movement which to the same extent moves the attached

slot-rails H, and consequently increases or diminishes the width of the slot upon bolts C being loosened up and the bracket forced forward or rearward.

Having thus described my invention, what I claim as new, and desire to secure by Letters Patent, is—

1. In a cable-wireway, the adjustable brackets A, adapted to sustain the slot-rails attached to and in combination with the ties B, for the purpose set forth.

2. In combination with a tunnel adapted to contain a cable for an endless wireway, the

slot-rails H, having a heavy rib, O', and a depending web, p, substantially as described, for the purpose set forth.

3. The bracket A, provided with lugs a a, in combination with the angle-iron stringer P, substantially as and for the purpose described.

In witness whereof I have hereunto set my hand.

HENRY CASEBOLT.
